W. S. HADAWAY, JR.
ELECTRIC RESISTANCE UNIT OR ELEMENT.
APPLICATION FILED JUNE 15, 1908.

918,535.

Patented Apr. 20, 1909

UNITED STATES PATENT OFFICE.

WILLIAM S. HADAWAY, JR., OF EAST ORANGE, NEW JERSEY.

ELECTRIC RESISTANCE UNIT OR ELEMENT.

No. 918,585.

Specification of Letters Patent. Patented April 20, 1909.

Original application filed September 28, 1907, Serial No. 394,745. Divided and this application filed June 15, 1908. Serial No. 438,572.

To all whom it may concern:

Be it known that I, WILLIAM S. HADAWAY, Jr., a citizen of the United States, and a resident of East Orange, in the county of Essex and State of New Jersey, have invented a new and useful Improvement in Electric Resistance Units or Elements, of which the following is a specification, this application being a division of application 10 Serial No. 394,745, filed September 28, 1907.

My invention relates to resistance elements or units for electric heating apparatus, and it has for its object to provide an element or unit which shall insure uniformity of 15 heat distribution over the surfaces of the apparatus in which it is embodied.

My invention is shown as applied to a plurality of bars of heat-conducting material which are assembled side by side, the 20 structure being very compact and rigid, and adapted for use in connection with stamping and embossing press machines, matrix drying presses and other apparatus, uniform heating of which is desired.

I have gained considerable advantage 25 over devices used in the prior art for similar purposes by insuring a uniform distribution of heat over the heating surface or surfaces.

Figure 1 of the accompanying drawings 30 is a plan view, with the cover removed, of a device equipped with my invention. Fig. 2 is a sectional elevation on the line II-II of Fig. 1. Fig. 3 is a side elevation of the same, and Fig. 4 is a detail view of a portion 35 of a resistance unit or element constructed in accordance with my invention.

Referring to the drawings, the device here illustrated comprises a plurality of bars 1, 2, 3, 4, 5, 6, 7, 8, 9, 10, and 11 which are of 40 substantially the same thickness and are assembled side by side in a flat box or frame 12, which comprises side strips 13 and 14, end strips 15 and 16 and cover plates 17 and 18. The bars are of different widths, the 45 narrower bars being located nearer the side strips 13 and 14 and the widest bar being located in the center.

Terminal members 19 and 20 are secured to and are insulated from the end strip 15 50 by binding nuts 21 and insulating washers 22. The outer extremities of the terminals are protected by a sheath 23 that is secured to the end strips by screws 24. The inner extremities of the terminals are screw- 55 threaded and are provided with nuts 25 by

means of which the ends of a resistance strip 26 may be electrically connected to the terminal members. The resistance strip, a section of which is illustrated in Fig. 4, is constructed of steel or other suitable material 60 and is provided with a plurality of slots 27 and 28 which extend inwardly from opposite edges of the strip and are arranged alternately so that a zigzag current-conducting path is provided. 65

As above indicated, one end of the strip is connected to one terminal of the heater and from this terminal the strip extends between the bar 1 and the side strip 13 to the other end of the frame, thence back between the bars 1 and 2, then away from the terminal end between the bars 2 and 3, and so on until some part of it is disposed between each two adjacent bars and its free end is then connected to the other terminal 70 of the device. It will, of course, be understood that the resistance strip may be arranged relative to the bars in any suitable manner and that my invention is not restricted to the arrangement shown. 75

The strip is insulated from the bars by mica or other suitable insulating material which is not injured by relatively high temperatures, and, in order that the ends of the bars may be maintained at substantially 80 the same temperature as their middle portions, without destroying or overheating the resistance strip at the corners where relatively sharp bends are made, the slots 27 and 28 are made closer together in those 85 portions of the strip which come close to the ends of the rods and the slots are omitted entirely at those portions of the strip in which the bends occur. It may be desirable 90 to reduce the width of the strip at these 95 points to some extent, as indicated in Fig. 4.

By making the middle bars of the heater materially wider than those nearer the outer edges, the temperature of the heating surfaces formed by the cover plates 17 and 18 100 is substantially uniform, since those parts which are farthest removed from the center of the mass are provided with the greater amounts of heating surface per unit volume.

The bars 1 to 11 are held in position in the frame formed by the parts 13, 14, 15, and 16 and the resistance strip is placed under pressure by means of a clamping rod 29 which is interposed between the assembled bars and the side strip 14 and which is 105

engaged by a plurality of clamping screws 30 which extend through tapped holes in the side strip 14. In some cases, it may be desirable to omit one or both of the plates 17 and 18, and, when this is done, the resistance strip may preferably be sunk into suitable slots which may be provided in the ends of the heating bars in order that they may be suitably protected from injury.

I claim as my invention:

1. A resistance unit comprising a conducting ribbon having a plurality of slots alternately open at opposite edges, said slots being unequally spaced to increase the resistance of predetermined portions of the ribbon.
2. A resistance element comprising a conducting ribbon having a plurality of lateral slots alternately open at opposite edges to increase the length of the current-conducting path therethrough, said slots being unequally spaced to increase the resistance of predetermined portions of the ribbon.
3. A resistance unit comprising a conducting ribbon having a plurality of groups of slots, alternately open at opposite edges, said groups being separated by material lengths of ribbon having a relatively large

current-carrying capacity, and said slots being unequally spaced to increase the resistance of the ribbon adjacent to the ends of the group.

4. A resistance unit comprising a conducting ribbon having a plurality of slots alternately open at opposite edges to increase the length of the current-conducting path therethrough, material lengths of ribbon having a relatively large current-conducting capacity being provided at the ends of the unit and constituting conducting leads therefor.

5. A resistance element comprising a conducting ribbon having a plurality of groups of slots alternately open at opposite edges, said groups being separated by material lengths of ribbon and similarly provided with end terminals having a relatively large current-carrying capacity.

In testimony whereof, I have hereunto subscribed my name this 12th day of June, 1908.

WILLIAM S. HADAWAY, JR.

Witnesses:

A. B. REYNDEBS,
BIRNEY HINES.

Correction in Letters Patent No. 918,535.

It is hereby certified that Letters Patent No. 918,535, granted April 20, 1909, upon the application of William S. Hadaway, Jr., of East Orange, New Jersey, for an improvement in "Electric Resistance Units or Elements," were erroneously issued to said "William S. Hadaway, Jr.," as sole owner of said invention; whereas the said Letters Patent should have been issued to *Hadaway Electric Heating and Engineering Company, a corporation of New York*, as owner of the entire interest in said invention, as shown by the assignments of record in this office; and that the said Letters Patent should be read with this correction therein that the same may conform to the record of the case in the Patent Office.

Signed and sealed this 18th day of May, A. D., 1909.

[SEAL.]

C. C. BILLINGS,

Acting Commissioner of Patents.
